US00D916444S

(12) **United States Design Patent** (10) **Patent No.:** **US D916,444 S**
Callow et al. (45) **Date of Patent:** **** Apr. 20, 2021**

(54) **SHOE**

(71) Applicant: **adidas AG**, Herzogenaurach (DE)

(72) Inventors: **Liz Callow**, Herzogenaurach (DE);
Angela Smith, Herzogenaurach (DE)

(73) Assignee: **adidas AG**, Herzogenaurach (DE)

(**) Term: **15 Years**

(21) Appl. No.: **29/697,489**

(22) Filed: **Jul. 9, 2019**

Related U.S. Application Data

(63) Continuation of application No. 29/614,532, filed on Aug. 21, 2017, now Pat. No. Des. 855,297.

(30) **Foreign Application Priority Data**

Feb. 21, 2017 (EM) 003761113

(51) **LOC (13) Cl.** **02-04**

(52) **U.S. Cl.**

USPC **D2/947; D2/952**

(57) **CLAIM**

The ornamental design for a shoe, as shown and described.

DESCRIPTION

FIG. 1 is a front medial perspective view of a shoe.
FIG. 2 is a front lateral perspective view of the shoe of FIG. 1.

FIG. 3 is a medial side view of the shoe of FIG. 1.
FIG. 4 is a lateral side view of the shoe of FIG. 1; and,
FIG. 5 is a rear view of the shoe of FIG. 1.
The broken lines show portions of the shoe that form no part
of the claimed design.

1 Claim, 5 Drawing Sheets
